UNITED STATES PATENT OFFICE.

FRANCIS C. BARTON, OF PHILADELPHIA, PENNSYLVANIA.

DESIGN FOR AN ABSORBENT-DISSEMINATOR.

45,174.

Specification for Design.

Patented Feb. 3, 1914.

Application filed September 16, 1913. Serial No. 790,378. Term of patent 7 years.

To all whom it may concern:

Be it known that I, FRANCIS C. BARTON, a citizen of the United States, residing at Philadelphia, in the county of Philadelphia and State of Pennsylvania, have invented a new, original, and ornamental Design for Absorbent-Disseminators, of which the following is a specification, reference being had to the accompanying drawing, forming part thereof.

The figure is a plan view in front elevation of an absorbent disseminator, showing my new design.

I claim—

The ornamental design for an absorbent disseminator as shown.

FRANCIS C. BARTON.
